UNITED STATES PATENT OFFICE.

SAMUEL A. CLICK, OF ELKHART, INDIANA, ASSIGNOR TO C. G. CONN, LTD., OF ELKHART, INDIANA, A CORPORATION OF INDIANA.

MUSICAL-INSTRUMENT CASE.

Application filed October 22, 1925. Serial No. 64,266.

This invention relates to cases for the transportation of dismantled clarionets, or the like.

The principal object of the invention is to provide a case in which the separated parts of a clarionet may be arranged in a very limited space. Another object of the invention is to provide a case of the character described in which a reed compartment is provided.

Other and more specific objects of the invention are mentioned and described herein.

The preferred embodiment of the invention is illustrated in the accompanying drawing, in which

Figure 1 is a top plan view of an open case for the separated parts of a clarionet in which the invention is built; Fig. 2 is a plan view of the interior frame illustrating the manner of forming the several compartments therein; Fig. 3 is a side elevational view thereof; Fig. 4 is an end view of the interior frame viewing it at the open end of compartment 3; and Fig. 5 is an end view thereof viewing it from the opposite end; Fig. 6 is a cross section on the line 6—6 of Fig. 1.

Similar numerals of reference indicate like parts throughout the several views on the drawing.

Referring to the details of the drawing, the numeral 1 indicates generally an open box-like case provided with a hinged cover 2, said case being adapted particularly to have the several separated parts of a clarionet arranged therein for transportation, the means whereof comprises the four compartments 3, 4, 5 and 6 hereinafter described in which the four separated parts of the clarionet, viz: the belled end section, the two intermediate sections, and the mouthpiece section (none being shown) respectively, are to be arranged. The case interior is provided also with the fifth compartment 7 adapted to contain reeds, or the like, for the clarionet.

The interior frame of the case which is so designed that the five compartments mentioned are formed thereby may comprise the two side longitudinal and parallel bars 8 and 9, the two inside or medial bars 10 and 11, also extending longitudinally of the case and substantially parallel with each other and said side bars, the end supporting bar 12 transversely arranged, and the two end supporting blocks 14 and 15, all of which are preferably made of wood and glued together and into the case interior. The forward end of

each of the bars 10 and 11 is flared outwardly at 16 and 17, respectively, to conform to the belled end of a clarionet, which is a well known construction, and the two inwardly projecting transverse cooperating lugs 18 and 19, respectively, of said bars, preferably integral therewith, serve to form a partition between compartments 3 and 4. The bars 10 and 11 are provided also with the inwardly projecting and cooperating lugs 20 and 21, respectively, to form one end partition or wall of compartment 4 and also the inner end wall or partition of compartment 7, the opposite end wall of the latter compartment being formed by the two inwardly projecting lugs 22 and 23, respectively, of the bars 10 and 11, adjacent the end of the latter. The end transverse bar 12 is provided with a recess 24 midway of its ends in which the ends of bars 10 and 11, including lugs 22 and 23, are arranged and secured adhesively, or otherwise.

The wood block 14 may support the cooperating forward ends of the side bar 9 and the medial bar 11, and the block 15, preferably wood, may support the cooperating forward ends of side bar 8 and medial bar 10, the bars 8 and 9 having spacer end lugs 25 and 26, respectively, to effect the proper interval between said bars and said medial bars, the opposite ends of the bars 8 and 9 being mounted in recesses 27 and 28, respectively, formed in the opposed ends of the end bar 12.

The numeral 31 indicates a box-like reed container, preferably open at the top thereof and arranged in the compartment 7. A cloth covering 29 may enclose the container 27, and a cloth covering 30, of velvet or other suitable material, may cover the wood frame formed of the several bars described.

My invention enables the production of a very short case for the transportation of the separated parts of a clarionet, and one that is cheap, substantial and readily handled.

I claim:—

1. An interior frame for a musical instrument case of the character described comprising in combination, two side bars spaced apart, two medial bars arranged between said side bars, substantially parallel and spaced from each other and from said side bars, each of said medial bars being provided with a plurality of laterally projecting and cooperating lugs forming a plurality of compartments between said medial bars, one of said compart-

ments having a belled end, and means for securing said bars together as a unit for arrangement within a case.

2. An interior frame for a clarinet case comprising in combination, two substantially parallel spaced apart side bars, two medial bars arranged between said side bars, substantially parallel and spaced from each other and from said side bars forming a single compartment between each medial and side bar, each of said medial bars being provided with a plurality of integral laterally projecting and cooperating lugs forming a plurality of compartments between said medial bars, one of said compartments having a belled end, and

means for securing said bars together as a unit.

3. In an interior frame for a clarinet case, two substantially parallel and spaced side bars, each of said bars being provided with a laterally projecting lug adapted to cooperate with each other to form a transverse partition between said bars, whereby a plurality of compartments are formed therebetween, one of said compartments having a flared end and another compartment having a container mounted therein.

In witness whereof I have hereunto affixed my signature this 19th day of October, 1925.

SAMUEL A. CLICK.
